SECRET LOCKING DEVICE

Application filed April 11, 1930. Serial No. 443,276.

This invention relates to secret door locks.

One object of the invention is to provide a door and jamb, or the equivalent, having improved association with a lock whereby the latter is operated through the clearance space between the door and the jamb.

Another object of the invention is to provide a device of the character described, including an improved secret door lock operative through the clearance space between the door and the jamb.

Another object of the invention is to furnish an improved lock of the type mentioned in which a key inserted through the space between the door and the jamb operates the lock with a movement of the key in a predetermined direction or plane according to the narrowness or other characteristics of the said space.

Another object of the invention is to construct a device of the nature set forth having a key operated tumbler means in improved association with the lock to operate the latter by a translational movement of the tumbler means.

Another object of the invention is the provision of a locking device including an improved tumbler means adapted to be locked in the open as well as the closed position of the lock.

A further object of the invention is to provide an improved lock having relatively few and simple parts, and which is relatively inexpensive to manufacture, compact, and reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the several views.

In the drawings:

Figure 1 is a horizontal sectional view of a door and jamb showing applied thereto a device embodying the invention.

Fig. 2 is a vertical sectional view of the same.

Fig. 3 is a vertical sectional view through the lock casing showing the mechanism therein.

Fig. 4 is a vertical view in elevation of the lock casing mechanism, the cover plate being removed, and a portion of the mechanism being in section.

Fig. 5 is a vertical sectional view taken on line 5—5 of Fig. 3.

Fig. 6 is a view similar to Fig. 4 but showing the tumbler means operated by a key.

Figs. 7 and 8 are side and edge views of a key.

Fig. 9 is a view in horizontal section of a door, a jamb and a strike, and showing an outside view of a modified lock embodying the invention.

Fig. 10 is a view in vertical section taken on line 10—10 of Fig. 9.

Fig. 11 is a view in elevation of the lock casing with a cover plate removed to show internal construction.

Fig. 12 is a view in vertical section taken on line 12—12 of Fig. 13.

Fig. 13 is a view in horizontal section taken on line 13—13 of Fig. 11.

Figs. 14 and 15 are side and edge views of a modified key.

Fig. 16 is an edge view in elevation of a further modification of the invention.

Fig. 17 is a view in side elevation of the same with a portion of the cover plate removed to show internal construction.

Fig. 18 is a vertical sectional view taken on line 18—18 of Fig. 17.

Fig. 19 is a view similar to Fig. 17, but with the cover plate and part of the mechanism removed to show the tumbler device.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying draw-

ings, therefore, is submitted merely as showing the preferred exemplification of the invention.

Generally described, the invention provides a door and jamb and a lock so arranged that the latter is concealed or adapted to be concealed and may be operated through a small space or slot. One possible embodiment of the invention includes the lock operated through the clearance space between the door and the jamb. The invention may be applied not only to doors, but also to windows, and generally to any types of closures. According to this invention, the operator passes a key or other tool through the clearance space mentioned, and causes said key to enter and operate the lock. The latter may include any suitable type of bolt or engagement and any desired mechanism for actuating the bolt. The movement of the key may be in the plane of the slot or clearance space, longitudinally, laterally, or both. A key operated tumbler means may be used for movement in the desired direction on insertion of the proper key, and the said movement may be along the plane referred to. For instance, the tumbler means may be mounted for oscillation, and may be so constructed that it can be oscillated only by the proper key. The tumbler means thereupon retracts the bolt. The tumbler means may be so arranged that it can be locked in open position to avoid accidental locking of the lock.

It will be obvious that the invention can be used with sliding as well as with swinging doors.

Referring in detail to the drawings, 20 denotes a device embodying the invention. 40 The same may include a door 21, a jamb 22, a strike 23, and a lock casing 24. While the latter is shown mounted in the jamb, and the strike in the door, the location of the parts may also be reversed. In the embodiment shown, the lock casing is set into a recess 25 in the jamb and is mounted to project at 26 from the face 27 of the jamb. The door 21 has a recess 28 to receive the projecting portion of the lock casing, the recess 28, however, being spaced from the key operating side, or outside face 29 of the door. Accordingly the adjacent outside edges of the door and jamb are of uniform character and provide a uniform clearance space 30, which is analogous to a slot.

The lock casing 24 has a plate 31 whereby it is secured to the jamb by screws 32. The strike 23 may be set into the door and secured by screws 33. The strike has an opening 34 and the door a communicating recess 35, whereby a bolt 36 of the lock casing is engaged.

It will now be seen that all parts of the lock are disposed in spaced relation from the outside of the door, and substantially

concealed, as the clearance space 30 is usually quite narrow, particularly in well constructed buildings. The portion of the lock remote from the face 29 of the door may, of course, be accessible from the inner side 37 of the door for manipulation by a knob, or the like, according to the well known practice.

The lock casing has a supporting plate 38 therein which extends the full length and breadth of the casing, being fitted between the upper and lower and the side walls of the casing. The said supporting plate 38 is in proximity to the cover plate. Spacing the supporting plate from the cover plate is a flange 39 at one side of the casing and a flange 40 at the top thereof. The lower portion 41 of the supporting plate 38 is of a thickness equal to said flanges. Thus a recess 42 is provided between the parts 39, 40, 41 for housing with the cover plate 31 a key operated tumbler 43 hereinafter described.

Secured to the portion 41 of the plate 38 is a stationary sleeve 44 which extends to the rear wall 45 of the lock casing. Slidingly disposed in said sleeve is a bolt 46 extending outward through an opening 47 in the cover plate 31. The said bolt has a central slot 48 formed in the rear portion, while the sleeve has a registering slot 49 in the entire length thereof. Intersecting the bolt slot is a pin 50.

In the upper part of the lock casing is a stationary plate 51 mounted in any suitable manner. The plate 51 has alined elongated ears 52, 52, and 54 formed therein, extending through which are bearing pins 55 and 55a.

Taking around the pin 55 is a coil spring 56 having a portion 57 extending downward to bear on the pin 50 to tend to project the bolt. Journaled on the pin 55a between the ears 53, 54 is a lever 58 which extends into the bolt slot 48 in advance of the pin 50. The said lever 58 has stop contact at 59 with the plate 38 in the projected position of the bolt.

Connected to the sleeve 44 is a portion 60 in which is secured one end of a stationary rod or shaft 61, the upper end whereof is fixed at 62 in the plate 51. Journaled on the shaft 61 is a sleeve 63 carrying spaced fingers 64, 65. The latter are of different characteristics and may also be angularly spaced to each other. The upper finger 64 is actuated by the key operated tumbler means 43 as hereinafter set forth to turn the sleeve, and thus to cause the lower finger 65 to move the lever 58, to act on the pin 50 and retract the bolt. Engagement between the lever 58 and the finger 65 may be facilitated by the recessed portion 66 in said lever.

Formed in the plate 38 is an opening 67 through which extends the finger 64 into the recess 42, the opening being sufficiently large

to permit the finger to be oscillated in said opening.

The key operated tumbler mechanism 43 includes a casing or yoke member 68 pivotally mounted at 69 on the plate 38 by a screw 70. The said casing member 68 has a side edge 71 spaced from the adjacent side wall of the lock casing to afford clearance for the pivotal movement of the member 68. At 10 its upper end, the member 68 has a portion 72 at the opening 67, whereby on pivotal movement of the member 68 parallel to the plate 38, the finger 64 is moved to cause retraction of the bolt.

15 The casing member 68 has fixed therein a portion 73 providing an opening 74 for a key 75. The latter may consist of a thin strip of metal of any desired conformation. Along one side edge of the key are indentations 76 for registering with tumblers 77 slidingly mounted in the portion 73. A pin 78 serves to limit the insertion of the key into the registering relation by co-operation with a portion 79 of the key.

20 Mounted in the casing member 43 is a slide member 80 which is movable along the portion 73. Said slide member has a plurality of bores housing expansion coil springs 81 and the pins 82 acted on by the springs. In the locked position of the tumbler means as 25 shown in Fig. 1, the slide member 80 abuts a side wall of the lock casing and prevents pivotal movement of the tumbler means. On insertion of the proper key 75, the slide member is released so that it is slidable relatively toward the right to permit the tumbler means to be oscillated counterclockwise to open the lock.

25 The key 75 is passed through the clearance space 30 between the door and jamb, and thence through the opening 83 in the lock casing, which key opening is in registry with the space 30. Thus the lock is concealed and operative only in a secret manner.

40 In Figs. 9 to 15 is shown a modification of the invention including a lock casing 85 mounted in a jamb 86, and a strike 87 in a door 88. The lock casing has an opening 89 registering with the clearance space 90 between the door and the jamb but spaced therefrom for concealment. A key 91 is insertable into said opening for operating the lock.

45 Mounted in the lock casing is a tumbler means 92 including a portion 93 pivotally mounted at 94. The portion 93 has a slot 95 to receive the key 91. An end 96 of the portion 93 is of fan tail shape and has tumblers 97 housed in bores 98 in a radial relation to the pivot 94. Coacting with the tumblers is 50 a fixed member 99 having pins 100, actuated by springs 101, all in symmetrical radial relation to the pivot 93.

55 It will be noted that the member 99 has more pins 100 than there are tumblers. This permits the tumbler means 92 to be locked in

the open as well as in the closed position of the lock as will now be described.

The key 91 has suitable recesses 102 on an end thereof to accommodate the tumblers and to radially actuate the same, for which purpose said recesses may have the requisite design and clearance, and with the tumblers properly related and spaced. In Fig. 12, the tumbler means is shown in an intermediate position. When the bores 98 register with any 70 corresponding number of the pins 100, the means 92 is locked against pivotal movement of the member 93. It is thus necessary to insert the key and move the same along the plane of the key slot 89, thus pivotally moving the member 93 to open or close the lock. Stop pins 103 may limit the movement of the member 93. Any suitable mechanism 75 may be actuated to operate a bolt.

Overlying the tumbler means 92, is a plate 85 104 which is set with a flange 105, 106 extending along a side and both ends of the lock. Mounted on said plate is a hook bolt 107, pivoted at 108, and actuated into locking position by a leaf spring 109. Connected 90 to said bolt is a link 110 having a pin 111 extending through a curved slot 112 into engagement with an arm 113 pivoted at 114. The said arm engages the member 93, whereby, on clockwise movement of the latter, the bolt 107 is moved upward to open the lock.

Secured over the bolt 107 is a cover 115, which is fastened in place by screws 116 that take into bosses 117 in the plate 104. The latter may be secured to the lock casing in 100 any suitable manner. The cover 115 affords space at 118 for the bolt 107.

To secure the lock casing to the jamb, the plate 104 may have a flange 118 receiving screws 119.

105 A strike 87 may consist of a plate having an opening 120 for receiving the bolt 107, there being a recess 121 in the door to accommodate the head of the bolt. The bolt thus acts in a direction parallel to the key 110 and at right angles to the plane of the door.

In Figs. 16 to 19 is shown a further modification of the invention which may embody all of the advantages and principles hereinbefore described, and is nevertheless of very simple 115 construction. This lock 122 has a casing 123, and a cover plate 124 for a hook bolt 125. The latter is pivoted at 126 on a plate 127 which is intermediate the side walls of the lock casing. A spring 128 tends to throw 120 the bolt into locking position.

A key operated tumbler means 129 is mounted on the opposite side of the plate 127. The means 129 is constructed according to the principle hereinbefore described for the 125 means 43. The lock casing has a slot 130 for a key to release the tumbler means and to permit the same to be oscillated about its pivot 131. At its upper part, the means 129 carries a pin 132 movable along a slot 133 130

to actuate an arm 134 of the bell crank bolt 125 for opening the same.

It will be appreciated that the parallel tumbler means 43 and 129 may be made to lock in open position of the lock according to the principle of the radial tumbler means 92.

Various changes and modifications may be made in the construction herein described, the drawings being submitted in an illustrative not in a limiting sense, the scope of the invention being defined in the following claims.

We claim:

15. 1. A locking device adapted to act between a door and a jamb, said locking device including a casing, a strike, interengaging means therefor, actuating means for the interengaging means, said actuating means having key operated tumbler means registering with the clearance space between the door and the jamb, and movably operative along the plane thereof, said tumbler means being disposed wholly within said casing, said casing having a key guiding slot along the said plane and in registry with said tumbler means.

20. 2. A locking device for a door and jamb, said device having key operated tumbler means, said tumbler means being disposed for accessibility through the clearance space between the door and the jamb, and with the axis of the tumbler means at an angle to the plane of the door, said tumbler means being mounted for oscillation along the plane of said clearance space to open or close the device.

25. 3. A locking device for a door and jamb, said device including a bolt, mechanism to actuate the bolt, said mechanism including a portion registering with the clearance space between the door and jamb and swingable along the plane thereof so as to be operative by a means insertable into said clearance space and movable longitudinally of the space to actuate said portion for opening or closing the lock.

30. 4. A locking device for interengaging a door and jamb, said device including a bolt, and mechanism to actuate the bolt, said mechanism including movable tumbler means communicating with the space between the door and jamb, said tumbler means being operative by a key to open or close the lock by movement of the key in the general direction of the plane of the door.

35. 5. A locking device for interengaging a door and jamb, said device including a bolt, and mechanism to actuate the bolt, said mechanism including an oscillatory key operated tumbler means communicating with the space between the door and the jamb, said tumbler means being operative by a key insertable through said space, said tumbler means being constructed to open or close the lock by a

swinging movement of the key along the plane of said space.

6. A locking device for interengaging a door and a jamb, said device being key operated from a side of the door, said device including a bolt, an actuating mechanism for the same, said mechanism having a key operated tumbler means, said tumbler means being spaced from said side of the door, said tumbler means registering with a space between the door and the jamb and being movable along the plane of the space.

7. A concealed locking device adapted to lock a door to a jamb, said door and jamb having a clearance space therebetween, the locking device being spaced from a face of the door, the door and jamb being adapted to conceal the locking device, said locking device including a casing, a strike, a bolt, and mechanism to actuate the same, said mechanism having a key operated tumbler means communicating with the clearance space between the door and jamb and being concealed between the latter.

8. A concealed locking device adapted to lock a door to a jamb, said door and jamb having a clearance space therebetween, the locking device being spaced from a face of the door, the door and jamb being adapted to conceal the locking device, said locking device including a casing, a strike, a bolt, and mechanism to actuate the same, said mechanism having a key operated tumbler means, said tumbler means communicating with the clearance space between the door and the jamb and being concealed between the latter, said tumbler means being constructed to receive a key inserted into said space, said tumbler means being swingably movable by the key along a plane parallel to said clearance space to actuate the mechanism for opening or closing the lock.

9. A lock for a plurality of relatively movable closure members having an open space therebetween, said lock including a casing mounted on one of the members and a strike on the other member, the casing having a portion projecting into said space at a point spaced from the outside of the members, and key operated tumbler means in said portion in communication with said space.

10. A lock for a plurality of relatively movable members having closure coaction along a plane, said members having therebetween a space at an angle to said plane, the lock including a casing and a strike mounted on respective members, the member having the strike being provided with a recess communicating with said members and spaced from the outside of the members, the strike being positioned in the recess, the casing extending across said space and into the recess, the lock mechanism in the casing, said mechanism being so arranged as to be actuatable through the said space.

11. A concealed lock for locking a door to a jamb, said door and jamb having a clearance space therebetween at an angle to the plane of the door, the lock being spaced from a face of the door, the door and jamb being adapted to conceal the lock, said lock including a casing, a strike, a bolt, means to actuate the same, and a key operated tumbler means for the actuating means, said tumbler means being so disposed as to receive the key through the said clearance space between the door and jamb, the tumbler means being mounted for oscillatory movement by the key along a plane determined by the said clearance space.
12. A device including a casing, a support swingably mounted therein, and key operated tumbler means mounted on the support, said tumbler means including a key receiving portion in proximity to the pivot and secured in fixed relation to the support, and a complementary relatively movable portion slidably mounted on the support and engageable with a relatively stationary element of the casing for preventing tilting movement of the support in the locked position of the tumbler means, whereby upon insertion of a key the complementary portion is slidable into released position for permitting swinging movement of the support.

In testimony whereof we affix our signatures.

CARL J. HAGSTROM,
GOTTHARD E. HAGSTROM.
